DES 2178

D. K. Albright, of Philadelphia, Penn. &
L. H. DeLange, of Bordentown, New Jersey.
Letter Patent No. 2178-Dated Oct. 10-1865.

Design for a Hat.

The schedule referred to in these letters Patent and making part of this design.

Drawn & sworn to my concern.

Be it known that we, D. K. Albright, of Philadelphia, Penn. & L. H. DeLange, of Bordentown, New Jersey, have invented a practical, new and original design for hats, as shown in the accompanying drawing with the following description of the same, to form a full, clear and exact description of the said design.

In the accompanying drawing A represents the body of the hat and B the brim.

The body A increases in diameter from the point right the point where it joins the brim, an enlargement of the shape as shown in the drawing being thus formed.

We claim

The shape and configuration, substantially as illustrated and by the accompanying drawing, of the hat, between the body and the brim.

For testimony whereof we have signed our names to this specification in the presence of two subscribing witnesses.

Witnesses:

Charles E. Foster,

J. J. W. John White,

Dan'l K. Albright
